(57) **CLAIM**

The ornamental design for a tool chest drawer or tray having an inside folding carrier handle, as shown and described.

DESCRIPTION

FIG. 1 is a perspective view of a tool chest drawer or tray having an inside folding carrier handle showing our new design, with the carrier handle in its stored position;

FIG. 2 is a top view thereof;

FIG. 3 is a side view thereof, the opposite side view being the same;

FIG. 4 is an end view thereof, the opposite end view being the same;

FIG. 5 is a perspective view thereof, with the carrier handle in its carrying position;

FIG. 6 is a top view thereof, with the carrier handle in its carrying position;

FIG. 7 is a side view thereof, with the carrier handle in its carrying position, the opposite side view being a mirror image;

FIG. 8 is an end view with the carrier handle in its carrying position, the opposite end view being a mirror image; and,

FIG. 9 is a bottom view thereof.

The tool chest and the pulls on the drawer or tray, both shown in phantom in FIG. 1, illustrate environment and form no part of the claimed design.
